UNITED STATES PATENT OFFICE

2,431,955

FEEDING MECHANISM FOR AUTOMATIC GUNS

Desmond Walter Molins, London, England, assignor to Molins Machine Company Limited, London, England

Application November 23, 1943, Serial No. 511,455
In Great Britain November 23, 1942

3 Claims. (Cl. 89—33)

1

This invention concerns improvements in or relating to ordnance, and refers particularly to that kind of ordnance in which rounds are fed automatically to the gun from a receptacle and are thereafter fired automatically. For convenience, ordnance of this kind will be referred to as "a gun."

The specification of co-pending United States patent application Serial No. 488,454, filed May 25, 1943, now Patent No. 2,418,656, issued April 8, 1947, describes an automatic gun of this kind, in which a round being fed from a receptacle is moved into position at which the base of the round is engaged by a rammer, while the front portion of the round is pushed downwardly on to the top of the breech-block. In this arrangement a yielding cushioning lever is provided to break the fall of the front portion of the round, which moves over to one side of the breech guide down which it slides to the curved top of the breech-block.

For convenience, the front portion of the round will be referred to herein as the "nose" of the round.

It is found, however, that when the nose of the round is fed down rapidly in this way, there is sometimes a tendency for it to slide too far around the curved top of the breech-block, with the result that when the rammer moves forwardly, the nose of the round has not come completely to rest or is not correctly aligned with the breech.

A further difficulty which is sometimes experienced when feeding rounds having long, finely tapering noses, is that the nose of the round, which is resting on the curved top of the breech-block when the rammer moves forward, does not enter the breech, owing to the fact that the tip of the nose tends to jam in the angle formed by the face of the breech and the top of the breech-block.

It is an object of the present invention to overcome these objections, by provision of means whereby the nose of a round may be correctly aligned with the breech, and may be free to enter the breech, irrespective of the particular shape of the nose.

According to the present invention there is provided in feeding mechanism for an automatic gun, a support for the nose of a round about to be fed to the breech of the gun, said support being adapted to yield on forward movement of the round, in such a manner as to permit the nose of the round to drop.

The yieldable support may comprise a pivoted member adapted to press the nose of the round laterally against a reaction surface and capable

2

of being swung resiliently in a plane parallel to the gun barrel and trunnion axes, the arrangement being such that when the round is moved forward, the pivoted member is swung forwardly by reason of the frictional grip of the support and the reaction surface on the nose of the round. The pivoted member may be adapted to yield downwardly under the weight of the nose of a round, to cushion the fall of the nose of the round, and may be yieldingly held against both downward and pivotal movement by means of a coil spring.

Mechanism constructed in accordance with the invention will now be described by way of example with reference to the accompanying drawings in which—

Figure 1 is a front elevation of the breech of a gun showing the application of the invention thereto. For convenience the parts constructed according to the invention and a few parts to which they are attached, are shown in heavy lines while the normal breech mechanism is shown in fine lines.

Figure 2 is a plan of Figure 1.

Figure 3 is a side elevation of Figure 1.

Referring to the drawings, the construction is shown as applied to the gun described and shown in the specification of the aforementioned United States patent application Serial No. 488,454, and a reference to Figures 5 and 7 of said specification render it unnecessary to show the whole gun herein, particularly since the present invention is concerned with only a part. In the gun to which the invention is shown applied, there is a receptacle or magazine from which rounds are moved into the feeding position by the mechanism described and illustrated in the prior specification. A pivoted catch is provided to support the rear portion of a round which has just left the receptacle, and to maintain it in a position to be engaged by the rammer. This pivoted catch is adapted to be swung out of engagement with the round by the forward movement of the rammer when the rammer has gripped the base of the round.

A reciprocating member is provided for thrusting the nose of a round downwardly. All the mechanism referred to above is described in detail in the specification referred to.

The axis of the gun barrel is indicated in some of the views by the reference C—G and rounds are indicated by the reference R.

Referring to Figures 1 and 2, there are disposed in the path of the nose N of a round as it descends, two support members 1 and 2, one fixed

and one movable. The movable support 2 is shown as a pivoted member and so arranged as to be capable of swinging horizontally in a forward direction. The pivoted member comprises a vertical plate fixed to a vertical pivot-post 3, which is rotatable and axially slidable in a bracket 6. The pivot-post 3 is provided with a coil spring 7, the arrangement being such that the action of the coil spring tends to hold the pivoted member against forward pivotal motion. For this purpose the spring is formed as a torsion spring, and the member is held in the full line position Figure 2 against the twist of the spring by an abutment 8 on the bracket 6. The pivot post and pivoted member are also capable of moving downwardly for a limited distance against the pressure of the coil spring 7, a stop 9 on the lower end of the post determining the extent of the upward movement. The pivoted support has one downwardly sloping edge 10, which is arranged to engage the nose N of a round as it falls. The slope of this edge is such that the nose of a round as it falls into engagement with the fixed and movable support members 2 and 1 respectively, becomes firmly wedged between them. The pivot post 3 is provided with a projection 11 which extends into the path of an abutment 13 carried by the sliding breech-block 5 of the gun, the projection being so arranged that it is engaged by the abutment on the breech-block (shown closed in Figure 1) when the latter moves upwardly. This engagement ensures that the pivoted member moves upwardly to its highest position every time and avoids any possibility of sticking. The tension of the spring 7 is adjustable. The adjustment is provided by four holes 15 in the lower member of the bracket 6 and the pivot post is slotted at 16 to take the other end of the spring.

The pivot bracket 6 is fixed by the screws shown in Figure 3 to a plate 14 which is bolted to the breech ring 4. The plate has other functions not pertinent to the present invention and is used here merely as a convenient fixture. The fixed support 1 comprises a plate mounted on the side of the breech ring 4. This plate constitutes a reaction surface against which the nose is pressed upwardly by the movable support member.

The two support members are so disposed in relation to the breech of the gun as to hold the nose of the round shown in chain lines and marked N, in such a position that when the round is thrust forward by the rammer, the nose of the round will enter the breech.

The operation of the apparatus is as follows: The nose of the round falls on to the top of the breech ring 4 (see Figure 2) of the gun, which at that moment is approaching the end of the run-out position. On the completion of the run-out of the gun, the nose of the round falls on to the pivoted member 2 depressing the latter against its coil spring. This has a cushioning effect and tends to break the fall of the nose of the round.

By reason of the fact that the pivoted member engages the nose of the round with a downwardly sloping face, the nose is wedged against the reaction surface constituted by the fixed support 1, and is unable to fall any further. This position is indicated by the chain line circle N in Figure 1.

The rammer then moves forward, carrying the

round with it. The frictional engagement of the round with the pivoted member 2 is sufficient to ensure that as the nose of the round moves forward, the pivoted member is swung forwardly, see Figure 2. The pivoted member is thus moved out of engagement with the nose of the round, permitting the round to drop freely.

Continued movement of the rammer thrusts the round, which finally assumes the position shown in Figure 1 where the end of the cartridge case is shown by two chain line circles marked R, into the breech, after which the breech is automatically closed and the round fired, all in the manner described in the specification referred to.

On upward movement of the breech-block 5 during said closing movement, the abutment 13 carried by the breech-block engages the projection 14 on the pivot post of the movable support, 20 and thus thrusts the movable support upwardly if it has not already been returned by the spring 7. The pivoted member is thus prevented from remaining in a depressed position, as it might do if for any reason the upward pressure of its coil 25 spring failed to move it upwardly to its highest position. If the pivoted member were to remain depressed it might foul the spent case of the round as it is ejected from the breech after the round has been fired, and it is to prevent 30 this possibility that the arrangement described above is provided.

In this way the pivoted member is moved to a position in which, when the gun is fired and the spent case ejected, the latter passes beneath the pivoted member in being ejected.

What I claim as my invention and desire to secure by Letters Patent is:

1. Feeding mechanism for an automatic gun comprising a yieldable pivoted support member 40 and means having a fixed reaction surface against which said member is adapted to press the nose of a round, said member being mounted for resilient swinging movement about a vertical axis, the arrangement being such that when the round 45 is moved forward, the pivoted member is swung forwardly by reason of the frictional grip of the support and the reaction surface on the nose of the round.

2. Feeding mechanism as claimed in claim 1, 50 wherein the pivoted member is yieldably mounted to move downwardly under the weight of the nose of a round, to cushion the fall of the nose of the round.

3. Feeding mechanism as claimed in claim 1, 55 wherein said pivoted member is yieldably mounted to move downwardly under the weight of the nose of a round, said resilient swinging mounting and downwardly yieldable mounting comprising a coil spring supporting said member and torsionally resisting its swinging movement.

DESMOND WALTER MOLINS.
